[57] ABSTRACT

This invention relates to casing for rollers or bolts for use in sliding door fittings. Such casings may be in the form of a major segment of a circle with the bounding chord located along the edge of the sliding door. In order to fit these casings without screws the outer sidewall has previously been made with elastically deformable toothing, but this itself has led to difficulties in removing the casing. In order to make the casing capable of revolution through 90° and still have a clearance between the bounding chord and the edge of the aperture in the door edge, the bounding chord is made shorter than the side of the inscribed square to the circle, i.e., the height of the arc of the segmental casing is not more than 86 percent of the diameter of the circle.

CASINGS FOR A ROLLER OR BOLT IN A SLIDING DOOR FITTING

The invention relates to a casing for a roller or bolt in a sliding door fitting said casing having a chamber in which the roller may be mounted or the bolt guided, and the space having a contour in the form of a segment of a circle and is covered on its outwardly directed side by a plate. The sidewall surface of the segmented contour is preferably toothed.

Casings of this known kind are fitted by insertion into recesses previously formed in the edge region of the sliding door in such a manner that the bounding chord of the circular segment of the casing coincides with the edge of the sliding door. In an earlier form of construction the casing was secured in this position by means of screws.

Apart from the additional expense entailed by at least two screws per casing, the additional labor required for fastening in this manner, namely the predrilling of the sliding doors and screwing-in at least two screws per casing, was however found to be disadvantageous. Furthermore, it has been found that casings secured by screws in this manner are not sufficiently secure in operation, since on the shrinkage of the wood or as the result of mechanical stresses the screws may become loose and finally be completely detached during the sliding of the door, so that the casing falls out and the furniture fitting is not usable until it is segmented.

This recently led to the development of casings which are made of plastics materials and in which part of the sidewall of the chamber receiving the roller or bolt is provided with elastically deformable external toothings. Given suitable dimensions of the recess provided to receive the casing, it is thus possible for the casing to be driven into the recess by only a few light blows, while the teeth of the external toothings bend over and firmly wedge the casing in the recess without any fastening by special retaining means, such as screws being required.

It has however now been found that in this more recent construction it is very difficult to remove the casing from the sliding door, for example when this is necessary because of a defect, and that this can in fact be done in almost all cases only by damaging the sliding door and/or the casing. The invention is intended to provide a remedy in this connection, that is to say to provide a casing which can be removed without difficulty, while being equally well secured in the fitted position as known constructions.

The casing according to the invention is characterized in that the height of the arc of the circular segmental casing amounts to not more than 86 percent of the diameter of the corresponding complete circle, that the sum of the arc height and the projection of the roller is smaller than the diameter of the corresponding complete circle, and that at least the plate is provided with abutments for the detachable coupling of the casing to a tool by means of which the casing can be turned in the recess receiving it.

This development is based on the realization that because of its circular segmental shape the casing can be turned in the recess and thereby brought into a position in which part of the sidewall of the space receiving the roller or bolt and constituting the adhering surface

projects freely upwards out of the recess and beyond the edge of the sliding door so that the adhering surface and the pressure applied thereby are reduced and the casing can be removed from the recess.

The chord of the circular segment of the casing moves inwards into the recess when the casing is turned and it is important that after turning through 90° this chord should still just have a point of intersection with the opening of the recess, or that twice the length of the arc cut off (= the arc cut off and moving into the recess when the casing is turned through 90° + the arc which on the turning of the casing through 90° moves out of the recess and projects freely beyond the edge of the sliding door) is slightly greater than $r\pi$.

These realizations are embodied in a first feature of the invention, according to which the height of the arc of the circular segmental casing should not amount to more than about 86 percent of the diameter of the corresponding complete circle. This may be calculated from consideration of the square inscribed in a circle. The further feature of the invention, according to which the sum of the arc height and the projection of the roller is smaller than the diameter of the corresponding complete circle, ensures that the casing will be free to turn in its recess without being hindered by the roller. The third feature, according to which at least the plate is provided with abutments for the detachable coupling of the casing to a tool, facilitates the turning of the casing in its recess.

In further development of the invention the abutment provided on the plate comprises two bores spaced apart from one another. The diameter of these bores is advantageously slightly larger than the diameter of the pins of a tool which is known in itself and which is suitable for transmitting torque, so that after its pins have been inserted into the bores of the plate said tool need merely be turned in order to turn the casing in its recess.

A preferred example of the embodiment of the invention is illustrated in the drawings, in which:

FIG. 1 shows a roller casing and a bolt in the fitted position.

FIG. 2 a roller casing after being turned through 90° to the position permitting removal of the casing, and

FIG. 3 is a rear view of a roller casing according to FIGS. 1 and 2.

The construction of the casings 1 illustrated in FIGS. 1 and 2 in the recesses provided to receive them can be seen particularly in FIG. 3. A casing 1 of this kind contains a space or chamber 5 which has the shape of a segment of a circle and is bounded at the rear by a real wall 2, at the side by a preferably externally toothed sidewall 3, and at the front by a plate 4 and in which a roller 6 is mounted or a bolt 7 is guided. The toothed contour cooperates with the side of the recess to provide a resistance for preventing accidental turning of the casing. The teeth are shown in FIG. 3. In the case of the bolt casing 1 the plate 4 has a slot 8 to guide an adjusting wedge 9 serving for the displacement of the bolt 7.

Whereas in FIG. 1 the chord 10 of the circular segment 1 of the casing coincides with the edge 11 of the sliding door, which is only partly indicated, in FIG. 2 it extends perpendicularly thereto. The casing 1 has been turned into this position by means of a plier-like tool

which is provided on the side of each of its jaws with a pin, these pins being adapted to be inserted into bores 12 in the plate 4; when this tool is turned the casing 1 must follow this movement.

Since in the position of the casing 1 shown in FIG. 2 the complete circle corresponding to the circular segment 1 of the casing has only less than 50% of its circumference bearing against the sidewall 13 of the recess, and since in addition a slight clearance exists between the chord 10 of the circular segment 1 of the casing and the line of intersection 14 (shown on the right in the drawing) of the sliding door edge 11 and the sidewall 13 of the recess, and also between the intermediate roller 6 and the side wall 13 of the recess, the casing 1 can be displaced slightly to the right and downwards, so that it is free on all sides from the sidewall 13 of the recess and can without difficulty be lifted out of the latter.

In order to achieve a clearance between the chord 10 and the corresponding gap in the edge 11 after the casing has been turned, it is necessary for the length of the chord to be greater than the length of the side of a square inscribed in the complete circle corresponding to the circular segment. A condition for this is that h , the height of the arc of the segment, should be less than $(2 + r^2)/4 \times d$ the diameter of the complete circle. This can be alternately expressed approximately as 86 percent of the diameter of the complete circle. The project p of the roller must clearly be such that $h + p$ is less than d , or the rotation through 90° would not be possible.

In the preferred example of embodiment of the invention illustrated in the drawing the plate 4 extends beyond the side-wall 3 of the space; the casing 1 can thus be supported on the sliding door surface by means of the laterally projecting portion of the plate, thus providing the advantage that the recess receiving the casing 1 is completely covered. If, however it is desired that the casing 1 should for example be mounted flush in the recess, it is advisable to omit the laterally project-

ing portion of the plate, so that the peripheral line of the plate 4 coincides with the sidewall 3 of the space 5.

I claim:

1. A casing for a roller or bolt of a sliding door fitting which casing contains a chamber which has a sidewall in the form of a major segment of a circle to be rotatably received in a similarly shaped recess having a mouth formed in the edge of the door and is covered on its outwardly directed side by means of a plate, the chamber being adapted to receive a projecting roller, or a bolt, at least the plate being provided with abutments for the detachable coupling of the casing to a tool, the sum of the arc height and projection of the roller being smaller than the diameter of the corresponding complete circle, whereby the casing can be turned by means of said tool, in the recess receiving it, from a first position, in which the chord of the segment formed by the sidewall coincides with the edge of the door and the roller or bolt projects beyond the edge of the door, to a second position, in which the said chord is perpendicular to the edge of the door; the height of the arc of the circular segment amounting to not more than 86% of the diameter of the corresponding complete circle, whereby when the casing is in said first position it is secured against movement out of the recess, but when the casing is in said second position, it can be withdrawn from the recess through the mouth thereof.

2. A casing according to claim 1, characterized in that the abutment provided on the plate comprises two bores spaced apart from one another.

3. A casing according to claim 2, characterized in that the diameter of the bores is slightly greater than the diameter of the pins of a tool which is known in itself and which is suitable for transmitting torque.

4. A casing according to claim 1, characterized in that the sidewall has a toothed contour for cooperating with the side of the recess for providing a resistance for preventing accidental turning of the casing.
